[57]

ABSTRACT

A hockey game comprising a playing board upon which is placed indicia for use by a simulated home team and a simulated visiting team. Each team is provided with player blocks for a center, a right wing, a left wing, two defense men and a goalie. The goalie player block is subdivided into right, left and middle blocks for purposes of the play. The board is further inscribed to indicate a home team scoreboard and a visiting team scoreboard. Each team is provided with a three dimensional goalie, three three dimensional scoreboard markers and a deck of 30 game cards. A three dimensional puck and a pair of dice complete the game apparatus.

HOCKEY GAME

BACKGROUND OF THE INVENTION

The present invention relates generally to the field of games, and more particularly, is directed to a hockey game suitable for playing indoors upon a game board.

The game of ice hockey has long been an exciting spectator sport and many teams, both professional and amateur, are well established and engage in regularly scheduled sporting events. More recently, professional ice hockey has become one of the leading spectator sports and each year draws many hundreds of thousands of spectators. Due to the increased popularity of the actual sport, there is also an increased need for a comparable, simulated board type of game suitable for playing at home. One such game has been described in U.S. Pat. No. 3,204,966.

SUMMARY OF THE INVENTION

The present invention relates to a simulated hockey game, and more particularly, is directed to a board type hockey game which includes suitable indicia and suitable apparatus to simulate in a meaningful manner the plays of an actual ice hockey game.

The present invention incorporates a game board having player blocks for the hockey players of each team designated thereon. Each team player blocks include a center, right and left wings, right and left defense men and a goalie. The goalie player block is subdivided into right, middle and left areas to enhance the play. Each team has a three dimensional goalie and three three dimensional scoreboard markers. The scoreboard markers are employed with scoreboards which are inscribed upon the playing board surface to provide readily identifiable means for keeping score.

A plurality of game cards are provided for each team and these cards control the play of the game, such as checking, passing and shooting for the various players of each team. By employing the game cards and by judiciously placing the goalie in one of the three subdivided goalie blocks, plays can be made by the opposing players until such time as a score is tallied. The player having the most scores at the end of three simulated playing periods would be the winner.

It is therefore an object of the present invention to provide an improved hockey game of the type set forth.

It is another object of the present invention to provide a novel hockey game which employs a game board having inscribed thereon indicia in the form of player blocks to designate the playing area for each player of each team.

It is another object of the present invention to provide a novel hockey game wherein indicia is inscribed upon a playing board in the form of player blocks and scoreboards wherein all of the plays of a usual hockey game may be simulated and a readily visible record of the scores can be maintained directly upon the board surface.

It is a further object of the present invention to provide a novel hockey game which includes a playing board and designated areas which are inscribed upon the board to represent the various players of each team, one designated area representing the goal, the goal area being sub-divided into right, middle and left blocks for game conducting purposes.

It is another object of the present invention to provide a novel hockey game that is inexpensive in manu-

facture, simple in design and trouble-free when in use.

Other objects and a fuller understanding of the invention will be had by referring to the following description and claims of a preferred embodiment thereof, taken in conjunction with the accompanying drawings wherein like reference characters refer to similar parts throughout the several views.

BRIEF DESCRIPTION OF THE DRAWINGS

10 FIG. 1 is a top perspective view of a hockey game game board constructed in accordance with the present invention.

15 FIG. 2 is a top plan view of the game cards which control the play of one team.

15 FIG. 3 is a bottom plan view of one of the play cards of FIG. 2 showing that the card controls the play of the home team.

20 FIG. 4 is a bottom plan view of one of the play cards of FIG. 2 showing that the card controls the play of the visitors team.

25 FIG. 5 is a perspective view of a goalie, the goalie being colored to correspond to the color coding of the game cards of one team, for example, red to indicate the visitors team.

25 FIG. 6 is a perspective view of the other goalie which is color coded to correspond to the color of the second team, for example, the color blue to indicate the home team.

30 FIG. 7 is a perspective view of the three scoreboard markers for one team, the markers being color coded, for example, with the color red to indicate the visitors team.

35 FIG. 8 is a perspective view of the three scoreboard markers for use when the other team, for example, the color blue to indicate the home team.

FIG. 9 is a perspective view of the puck which is used in playing the game.

FIG. 10 is a perspective view of a pair of dice which are employed to play the game.

DESCRIPTION OF THE PREFERRED EMBODIMENTS OF THE INVENTION

Although specific terms are used in the following description for the sake of clarity, these terms are intended to refer only to the particular structure of my invention selected for illustration in the drawings, and are not intended to define or limit the scope of the invention.

Referring now to the drawings, I show in FIG. 1, a game board 10 which is generally sub-divided into a visiting team area 12 and a home team area 14. Each team area 12, 14 is inscribed with a plurality of player blocks to represent the relative positions of the various players of each team. Each team area includes a center player block 16, 16', a right wing player block 18, 18', a left wing player block 20, 20' and two defense men player blocks 22, 22' and 24, 24'. The board is further inscribed with a goalie area 26, 26' to receive the three dimensional goalies 34, 36 as hereinafter more fully set forth. Each goalie area 26, 26' is further subdivided into a middle area 28, 28', a left area 30, 30' and a right area 32, 32' for shot blocking purposes in accordance with the play of the game. Additionally, the face of the game board 10 is inscribed to provide the visitor and home team score boards 38, 38'.

Still referring to FIG. 1, the face of the board is provided with a puck area 40, to designate the position of

the puck 50 for playing the game as hereinafter more fully set forth. Each score board 38,38' is subdivided into three playing period columns 52,52', 54,54', 56,56' to indicate the scoring in each of three playing periods. The columns 52, 54, 56 are further subdivided into horizontal score areas 58, 58' to indicate the number of scores in each of the three periods. The three dimensional score board markers 60, 62, 64, 66, 68, 70 are each respectively placed upon one of the columns 52, 52', 54, 54', 56, 56' to visually indicate directly upon the board all of the scoring at any particular point in time in the game.

In FIG. 2 I show the play sides 72 of the various play cards 74 which are used by each play team. Each set of cards comprises three defense men check cards 76, 78, 80; four defense men pass cards 82, 84, 86, 88; three left wing pass cards 90, 92, 94; five left wing shot cards 90, 92, 94, 96, 98; three center pass cards 100, 102, 104; four center shot cards 106, 108, 110, 112; three right wing pass cards 114, 116, 118; and five right wing shot cards 120, 122, 124, 126, 128.

As seen in FIGS. 3 and 4, the team side 130 of the play cards 74 are each designated with either the letter "V" or the letter "H" to designate whether the card belongs to the home team deck or the visiting team deck. It will be appreciated that thirty cards with identical play side 72 designations will be provided for each team to properly play the game. A pair of dice 132 are provided with the game for play purposes. Preferably, the various play cards 74 are fabricated of relatively flat, substantially two dimensional configuration to lie flat upon the surface of the game board 10. The goalies 34, 36, the puck 50, the score board markers 60, 62, 64, 66, 68, 70 and the pair of dice 132 are preferably three dimensional in configuration to facilitate movement of the parts and to generally add interest to the game.

In order to play the game, each player receives 30 game cards 74, a goalie 34 or 36 of his own color and three score board markers 60, 62, 64 or 66, 68, 70. The cards indicated with the H on the team side 130 are for the home team player and the cards marked with the V on the team side 130 are for the visiting player. Each set of 30 cards is placed on an unused pile on one side of the board with the team side 130 of the cards facing upwardly. The puck 50 is placed in the central puck area 40 until a play begins. One score board marker 60, 62, 64, 66, 68, 70 is used to score goals in each period in the designated columns 52,52', 54,54', 56,56'. The position of a goalie 34, 36 within the respective middle, left and right goalie areas 28,28', 30,30', 32,32' is determined by the defense player in the course of the play.

Each player rolls the dice at the beginning of the game and at the beginning of each play. The person rolling the highest number initially gets the puck 50 for his team. The player with the puck then rolls the dice 132 again to determine where the puck will be placed. In one embodiment, if the roll of the dice 132 is either 3, 6, or 10, the visiting team would place the puck in the right wing area 18' if the visiting team had the puck 50. Similarly, the home team would place the puck in the home right wing area 18 if the home team had the puck. If the roll of the dice was 5, 8 or 11, the visiting team would place the puck in the left wing area 20'. If the home team had the puck, the home team would place the puck in the home left wing area 20'. If the roll

of the dice was 4, 9 or 12, the puck would be placed in the correct respective visiting center area 16' or home center area 16. A roll of 2 or 7 on the part of the visiting team would place the puck in the defense area 22' or 24' and a roll of 2 or 7 by the home team would place the puck in the home defense area 22 or 24.

Once the position of the puck 50 is determined, the player with the puck must draw five cards from his unused pile. The player with the puck is known as the offense player. It is the object of the game for the offense player to attempt to score a goal to the opponents respective goalie area 26 or 26'. If none of the five cards drawn by the offense player has a shot play designated on the play side 72, then no goal can be scored for that hand and the cards must be discarded to a used card pile (not shown). If however, a shot card, for example cards 90, 92, 94, 96, or 98 is drawn, it must be a shot card that can be used. For example, if the puck 50 was positioned on the home center block 16 and one of the five cards 74 drawn by the home team offense player was card 106 which is inscribed, "player-center, play-shot to right", then the offense player would place the card face down on his "home center block" 16 under the puck 50 to prevent the defense player from seeing the play. At that point, the defense player should place his goalie 34 on one of the goalie areas 26, 28 or 30. If the defense player places his goalie on the right block 32, then no goal would be scored by the offense player. If the defense player had placed his goalie in the middle block 28, then the offense player would have scored a goal. The cards are revealed only after the defense player positions his goalie in one of the goalie areas 26, 28, 30 and only one shot can be used in a play. At the end of each play, the five cards 74 drawn by the offense player are placed in a used pile and are not used in other hands for the remainder of that period.

The offense player may pass the puck from its original position to another player block by employing one of the pass cards, for example card 100, 102 or 104. Whatever play is determined, the necessary card is placed face down upon the appropriate player block 16, 18, 20, 22 or 24. The offense player may make as many passes as he can, provided he has the game cards 74 to do so. The last position of the puck 50 must result in a shot, otherwise the hand is put aside and the cards for that hand is placed in the used pile (for the remainder of that period).

The defense player has the choice of drawing five cards from his unused pile or not playing that hand at all. This determination must be made before the position of the puck is determined by the offense player. If the defense player chooses to draw five cards, a checking card must be drawn to result in the possibility of any defensive play. Cards 76, 78, 80 are illustrative of the defense cards. After the offense player has placed his cards face down on his player blocks, then the defense player may place any checking cards on his defense-man player blocks 22, 22', 24, 24'. A checking card only blocks a shot to the defense player's goalie side; passes of the puck 50 by the offensive player are never checked. If the defense player has no checking card, then the defense player cards are put aside in the used card pile for the remainder of that period.

Whenever an offense player passes the puck, he must roll the dice 132 before the cards are revealed to determine whether the puck should be considered as "off side". If a 3 is rolled, then the puck is ruled as off-side

and all the cards of that hand are placed in the used pile. If any other number is rolled on the dice, then the play continues as usual. Each time an offense player scores a goal, he moves one of his score board markers 50, 62, 64, 66, 70 to the next highest number circled 5 in the respective columns 52, 52', 54, 54', 56, 56' on his area 12, 14 of the game board 10 for a designated period. The maximum number of goals scored in any one period is six and the maximum for the entire game is 18.

When both players have used up all of their 30 game cards 74, then that period is over. The used pile of cards is then shuffled and a new period begins. If only one player has cards 74 left, then that player may take up to 10 cards, provided the player with the cards wins 15 the "face off" by rolling the dice. This is called a "power play," giving a player a better chance of scoring at the end of that period. If the player who does have any cards left does not win the face-off by rolling the highest number of the dice, then that period is over 20 and a new period begins in the manner hereinbefore set forth.

Although I have described the present invention with reference to the particular embodiments herein set forth, it is understood that the present disclosure has 25 been made only by way of example and that numerous changes in the details of construction may be resorted to without departing from the spirit and scope of the invention. Thus, the scope of the invention should not be limited by the foregoing specification, but rather 30 only by the scope of the claims appended hereto.

I claim:

1. A simulated hockey game comprising: a playing board; a visiting team area designated on and occupying one half of said board; a home team area designated 35 on and occupying the remaining one half of said board; said team areas each being inscribed with a plurality of separate player blocks having indicia associated therewith identifying the blocks as a center, a right wing, a left wing, two defense men and a goalie, respectively; 40 said goalie blocks being disposed on opposing sides of said board and each being subdivided into blocks inscribed as right, middle and left, respectively;

a first goalie piece adapted to be placed in any one of the visiting team goalie blocks and a second 45 goalie piece adapted to be placed in any one of the home team visiting blocks;

a simulated puck;

chance means for determining, at the beginning each play, which participant of the game is to assume the role of the offensive and the defensive player, respectively, and for determining the offensive player's block in which said puck is to be initially placed;

a plurality of cards for the visiting team and a plurality of cards for the home team; said cards being sized to fit in said blocks; said cards in each plurality being variously provided on their faces with indicia designating either a defense play, a pass play, or a shot play to either a right, middle or left goalie block;

whereby the offensive player draws at random a plurality of cards which may designate a shot from the block in which the simulated puck has been initially placed as aforesaid to one of the defensive player's goalie blocks or which may designate a pass play from the block in which the puck was initially placed to another offensive player's block and a shot from the latter block to one of the defensive player's goalie blocks; said so designating cards being placed face down on the appropriate offensive player's blocks; said defensive player at that time placing his goalie in the goalie block to which he thinks a shot might be directed to thereby successfully defend against said shot and at his option drawing at random a plurality of cards any one of which may designate a defense against one of the aforesaid offensive shots.

2. A simulated hockey game in accordance with claim 1 wherein said playing board is inscribed with a score board area, said score board area having indicia associated therewith identifying portions as relating to the visiting team area and the home team area respectively and a plurality of three-dimensional score board markers selectively placed upon the score board area to indicate the score of the game, the said markers being divided into a plurality of visiting team markers and a plurality of home team markers.

3. A simulated hockey game in accordance with claim 2 wherein the player blocks, playing cards, goalie, score board area and score board markers respectively of the visiting team are all color coded to a same first color and of the home team are all color coded to the same second color.
